UNITED STATES PATENT OFFICE.

SAMUEL LANES, OF NEW YORK, N. Y.

COMBINED CHAIR AND BED.

1,261,040.

Specification of Letters Patent.

Patented Apr. 2, 1918.

Application filed April 19, 1917. Serial No. 163,248.

To all whom it may concern:

Be it known that I, SAMUEL LANES, a subject of the Emperor of Austria-Hungary, residing at New York, in the county of New 5 York and State of New York, have invented certain new and useful Improvements in Combined Chairs and Beds; and I do declare the following to be a full, clear, and exact description of the invention, such as 10 will enable others skilled in the art to which it appertains to make and use the same.

My invention relates to that class of devices capable for use either as a chair or a bed, and foldable to compact size for storage, moving, or whenever required.

The principal object of the invention is to provide a device of the class specified which is so constructed as to permit the arms of the chair to serve as braces for certain legs 20 of the bed.

Another object is to provide novel means for operating the back of the device and the foot section thereof simultaneously and for preventing excessive downward movement of said back before the supporting legs thereof are extended.

A further object is to construct the entire device in an extremely simple yet an effective manner, and with these several objects in view, the invention resides in the novel features of construction and unique combinations of parts to be hereinafter fully described and claimed, the descriptive matter being supplemented by the accompanying drawings which form a part of this specification, and in which:

Figure 1 is a perspective view of the improved device positioned for use as a straight backed chair;

Fig. 2 is a longitudinal section of the invention with the back and foot sections thereof in position to permit the occupant to recline;

Fig. 3 is a side elevation showing the device in position to be occupied as a bed; and

Fig. 4 is a side elevation showing the device folded.

In the drawings above briefly described, the numeral 1 designates a seat section supported on legs 2, whereas the numerals 3 and 4 have reference respectively to the back and foot sections of the improved article of furniture, both of said sections 3 and 4 being hinged to the seat section 1 so that they may swing to and between hori-

zontal and vertical positions. The several sections 1, 3, and 4 each include a suitable frame preferably constructed of angle iron for rendering the device rigid, yet at the same time comparatively light. The specific 60 construction of these frames is not involved in the present invention and will not therefore be illustrated or described in detail. It is to be observed, however, that a single sheet of canvas or the like 5 is stretched 65 between the several frames and is anchored at its edges by coiled springs 6. The provision of such a sheet of material is preferable, but it will be obvious that the same could well be dispensed with and that a 70 suitably constructed spring such as an ordinary bed or cot spring could be substituted, such changes obviously falling within the scope of the invention.

Arms 7 are pivoted at 8 to the side bars 75 of the back section 3 and in their front ends are formed with T-shaped notches 9 which, when the device is used as a chair, receive therein either front or rear studs 10 and 11 on the side bars of the seat 1. 80 By this arrangement, the back 3 may be held in a vertical position as shown in Fig. 1 or may be inclined as depicted in Fig. 2. The foot section 4 is moved simultaneously with the back 3 by front and rear links 12 85 and 13 respectively.

The links 12 are pivoted to the side bars of the foot section 4 and extend rearwardly therefrom, whereas the rear ends of the links 13 are pivoted to the side bars of the 90 back section 3, the rear ends of the links 12 and the front ends of 13, being pivotally connected as shown. Headed studs or the like 14 project outwardly from the rear legs of the seat 1 and slidably support the links 95 13 so that the latter serve as levers for operating the links 12 to automatically adjust the foot section 4 when the back 3 is adjusted.

The links 12 and 13 perform a further 100 function of limiting the downward movement of the back 3, before the supporting legs 15 thereof are extended for use. The links are caused to operate in this manner by the provision of a pivoted support 16 for the 105 foot section 4, and stops 17 for limiting the upward movement of the links 12. It will be observed that when the back and foot sections are respectively lowered and raised to place the device in condition for use as a bed, 110

the front ends of the links 13 exert an upward stress on the rear ends of the links 12. The latter, however, have by this time come in contact with the stops 17 and similarly 5 the support 16 has come into play to prevent downward movement of the foot section 4. The front ends of the links 12 are thus prevented from moving downwardly and consequently the rear ends thereof cannot yield 10 to the upward stress exerted thereon by the links 13, the result being that the back 3 will be supported against swinging downwardly on to the floor, until the legs 15 are lowered into operative position.

15 The stops 17 could well be of any suitable construction, but they are preferably in the form of strips of metal riveted to the side bars of the seat 1 and bent into the C shape depicted most clearly in Fig. 1. By this 20 construction, the lower ends of the stops limit the upward movement of the links 12, whereas the upper ends thereof serve to support the arms 7 when the structure is folded as shown in Fig. 4.

25 The legs 15 are pivoted at their upper ends to the side bars of the back 3, and adjacent their lower ends, said legs are provided with headed studs 18 for reception in the notches 9 of the arms 7 when the device is extended 30 for use as a bed, as illustrated in Fig. 3. The arms 7 thus serve the additional function of bracing the legs 15 although in some types of the invention, toggle links 19 may be provided as an extra precaution against 35 accidental movement of these legs.

40 The chair is of great use in apartments or living rooms where all available space must be utilized, it being obvious that the device may be used as a straight back chair (Fig. 1), a Morris chair (Fig. 2), or a bed or cot (Fig. 3). Furthermore, when its use is no 45 longer needed, the device may be folded compactly as illustrated in Fig. 4. When in this folded position, the back 3 rests on the seat 1 and the arms 7 are supported by the upper ends of the stops 17.

50 On account of the advantages derived from the specific construction shown and described, it constitutes the preferred form of the improved combination article of furniture. I wish it understood, however, that within the scope of the invention as claimed, numerous minor changes may be made without sacrificing the principal advantages.

I claim:

1. A combined bed and chair comprising a seat supported on legs, a back and a foot section hinged to said seat, front links pivoted to said foot section and extending rearwardly, rear links pivoted to said back at their rear ends and pivoted at their front ends to said front links, and means fixed in respect to the seat for slidably supporting said rear links, whereby they may act as levers for operating the front links to adjust the foot section automatically upon adjustment of the back.

2. A combined bed and chair comprising a seat supported on legs, a back and a foot section hinged to said seat, front links pivoted to said foot section and extending rearwardly, rear links pivoted to said back at their rear ends and pivoted at their front ends to said front links, means fixed in respect to the seat for slidably supporting said rear links whereby they may act as levers for operating the front links to adjust the foot section automatically upon adjustment of the back, means for supporting said foot section in raised position, and stops fixed in 70 respect to the seat and positioned in the upward path of said front links.

3. A combined bed and chair comprising a seat supported on legs, a back and a foot section hinged to said seat, front links pivoted to said foot section and extending rearwardly, rear links pivoted to said back at their rear ends and pivoted at their front ends to said front links, means fixed in respect to the seat for slidably supporting said rear links whereby they may act as levers for operating the front links to adjust the foot section automatically upon adjustment of the back, means for supporting said foot section in raised position, stops fixed in 80 respect to the seat and positioned in the upward path of said front links, and arms pivoted to the back and detachably connected with said seat, said stops being positioned to support said arms when the entire device is 85 90 95 100 folded.

In testimony whereof I have hereunto set my hand in the presence of two subscribing witnesses.

SAMUEL LANES.
